US0D1021355S

(12) **United States Design Patent** (10) Patent No.: **US D1,021,355 S**
(45) Date of Patent: ** Apr. 9, 2024

(54) **FOOTWEAR ARTICLE**

(71) Applicant: **Fuerst Group, Inc.**, Menlo Park, CA (US)

(72) Inventors: **Rory Fuerst**, Atherton, CA (US); **Chengkou Kue**, Centennial, CO (US); **Scott Labbe**, Brentwood, NH (US)

(73) Assignee: **FUERST GROUP, INC.**, Menlo Park, CA (US)

(**) Term: **15 Years**

(21) Appl. No.: **29/784,043**

(22) Filed: **May 17, 2021**

(51) LOC (14) Cl. **02-04**

(52) U.S. Cl. ..... **USPC D2/947**

(58) **Field of Classification Search**

USPC D2/964, 915, 947, 902, 906, 908, 916, D2/918, 925, 946, 948-962, 972, 977
CPC A43B 13/00; A43B 13/02; A43B 13/023; A43B 13/026; A43B 13/04; A43B 13/08; A43B 13/10; A43B 13/12; A43B 13/14; A43B 13/141; A43B 13/143; A43B 13/16; A43B 13/18; A43B 13/181; A43B 13/187; A43B 13/189; A43B 13/20; A43B 13/22; A43B 13/223; A43B 13/24; A43B 13/28; A43B 13/30; A43B 13/32; A43B 13/34; A43B 13/36

(57) **CLAIM**

The ornamental design for a footwear article, as shown and described.

DESCRIPTION

FIG. 1 is a right side view of a footwear article according to the claimed design.

FIG. 2 is a left side view of the footwear article.

FIG. 3 is a front view of the footwear article.

FIG. 4 is a rear view of the footwear article.

FIG. 5 is a top view of the footwear article; and,

FIG. 6 is a bottom view of the footwear article.

The dash-dash broken lines in the drawings illustrate portions of the footwear article that form no part of the claimed design.

The dash-dot-dash broken lines in the drawings represent stitching that forms no part of the claimed design.

The surface line shading is included for clarification purposes.

1 Claim, 6 Drawing Sheets
